UNITED STATES PATENT OFFICE.

GUY EVERETT SMITH, OF OKLAHOMA, OKLAHOMA

TOOL-HOLDER.

1,357,123.

Specification of Letters Patent. Patented Oct. 26, 1920.

Application filed September 23, 1919. Serial No. 325,685.

To all whom it may concern:

Be it known that I, GUY EVERETT SMITH, a citizen of the United States, residing at Oklahoma, in the county of Oklahoma and State of Oklahoma, have invented new and useful Improvements in Tool-Holders, of which the following is a specification.

This invention comprehends the provision of a tool holder primarily designed for butchers' use, and adapted to support and maintain such tools as cleavers, saws, knives, skewers, steels and the like, in convenient reach of the user.

In carrying out my invention use is made of an arm curved to conform to the curvature of the meat block upon which it is pivotally mounted, so that the said arm with the tool suspended therefrom can be swung close to the block in an out-of-the-way position when its use is not desired.

The nature and advantages of the invention will be better understood when the following detailed description is taken in connection with the accompanying drawing, the invention residing in the construction, combination and arrangement of parts as claimed.

In the drawing forming part of this specification, like numerals of reference indicate similar parts in the several views, and wherein:

Figure 1 is a view showing the tool holder supported upon a meat block and the tools in their position upon the holder.

Fig. 2 is a top plan view showing the position of the holder when its use is not desired.

Fig. 3 is a sectional view taken on line 3—3 of Fig. 1.

The holder constructed in accordance with my invention, is formed from a single blank of any suitable material, and includes an arm 10 adapted to be arranged horizontally, and from one edge of which depends a reinforcing flange 11. This flange 11 gives the arm an L-shaped formation in cross section. The flange 11 is tapered from one end to the other along one of its edges, and this flange is rolled at its widest edge to provide a pivot post 12. As shown the post projects above and below the opposite edges of the flange 11 and is adapted to be received in an opening 14 of the lugs 15 forming part of a resilient bracket 16. As shown in this par-

ticular instance the bracket 16 is secured to one side of a meat block A, although the bracket can be secured to any suitable support. The lugs 15 project at right angles from the body of the bracket, while the post 12 is provided with annular grooves 17 which receive the edges of the opening in said ears, thus preventing casual separation or derangement of parts under the weight of the tools. As above stated the arm 10 is curved, so that when the use of the tools and holder is not desired, the arm can be swung close to the block with the tools suspended therefrom, as clearly illustrated in Fig. 2.

The arm 10 at a point adjacent the post is provided with spaced openings of a certain diameter, these openings being indicated at 20 and adapted to receive and support a number of skewers 21. At a point adjacent the free end of the arm, the latter is provided with an opening 22 of proper size, to receive and accommodate the steels 23. The arm is provided with a plurality of parallel slots 24 suitably spaced apart, and opening at one edge of the arm. These slots communicate at their opposite ends with openings 25. Certain of the openings 25 are of a size to accommodate cleavers not shown, while other of said openings are of proper size to receive and support therefrom different forms of butcher knives, not shown. As shown in Fig. 1, the holder may be swung away from the block during the day occupying a position to support the various tools used by the butcher, in convenient reach of the latter. The back of the knives or other tools are inserted into the proper slots and openings communicating with the ends of the slots and consequently the tools are supported in the manner so that when their use is again desired, the tools can be taken hold of and removed from the holder with the tools in their proper position for use, not necessitating the changing of the grip upon the tool. At the end of the day, just prior to closing of the shop, the tools are arranged within the proper slots of the holder, after which the holder or arm 10 is swung close to the block in the manner illustrated in Fig. 2.

While I have shown and described what I consider the preferred embodiment of the invention, I desire to have it understood that I do not limit myself in this connection

and that such changes may be resorted to when desired as fall within the scope of what is claimed.

What I claim is:—

- 5 A tool holder of the character described comprising in combination with a fixed support, a bracket secured to the support and including spaced lugs, an arm longitudinally curved and including vertically and horizontally disposed portions, a hollow post formed at one end of the arm and pivoted
- 10

between the lugs of said bracket, whereby the arm is pivotally mounted for horizontal swinging movement, the horizontally disposed portion of the arm having slots opening at the free edge thereof, and terminating at their opposite ends to provide openings of different sizes, said slots being provided for the reception of the tools. ¹⁵

In testimony whereof I affix my signature. ²⁰

GUY EVERET SMITH.
